BARBERS' AND BEAUTICIANS' NECK
DUSTER

Clinton E. Stroup, Mansfield, Pa.

Application August 13, 1952, Serial No. 304,152

2 Claims. (Cl. 15—131.1)

1

This invention relates to a neck duster especially useful in barber and beautician shops and it consists in the constructions, arrangements and combinations herein described and claimed.

It is a particular object of the invention to provide a neck duster wherein a disposable container for antiseptic powder is employed, the container being provided with a perforated top, to permit passage of the powder to the bristles of a brush head having perforations aligned with the perforations of the perforated top, the container and the brush head being detachably secured together by means of a handle.

More particularly, it is an object of the invention to provide a neck duster wherein a handle is so constructed as to cooperate with a disposable antiseptic container and a bristle mounting head, to permit separation thereof in order to dispose of the container and sterilization of the bristle mounting head, thereby meeting state health regulations.

It is a still further object of the invention to provide a neck duster which is of simple construction, of few parts and which may be sold at a low cost.

Additional objects, advantages and features of invention will be apparent from the following description, considered in conjunction with the accompanying drawing, wherein,

Figure 1 is a cross section on the line 1—1 of Figure 2.

Figure 2 is a cross section on the line 2—2 of Figure 1.

Figure 3 is a cross section on the line 3—3 of Figure 1, and

Figure 4 is a side elevation of the powder container prior to its installation on the handle and bristle head.

Reference is first made to Figure 1 of the drawing, wherein a dusting brush is generally indicated at 10, consisting of a handle member 11, a powder receptacle 12 and a bristle head 13 which are detachably connected together as will be described.

The handle 11 is formed with a reduced coaxial extension 14, and a further reduced threaded coaxial shank 15.

The receptacle 12 in the present instance is shown as of cylindrical form, although such shape is not arbitrary so long as it comprises a bottom wall 16, a continuous upright wall 17 and a top wall 18. Centrally of the bottom wall 16 an opening 19 is formed by virtue of a sleeve 20 secured between the bottom wall 16 and the top wall 18. The top wall 18 is preferably cemented

to the wall 17 of the receptacle 12 after filling with a suitable antiseptic powder indicated at 21. The top wall 18 is formed with a multiplicity of apertures 22 for a purpose presently to be explained.

A bristle head 13 is employed, of circular formation, of a diameter corresponding to the diameter of the receptacle 12 and is seated on the top wall 18 for securement thereto. The head 13 is formed with a multiplicity of tapered openings 24 for securely mounting a respective tuft of bristles 25. The bristles 25 are arranged in radiating rows, as clearly shown in Figure 2, and between the rows, apertures 26 are formed also arranged in radiating rows. The apertures 26 are aligned with the apertures 22 of the top wall 18 and in order that ready and proper alignment of these apertures may be effected, guide pins 27 formed integrally with the top wall 18 seat in recesses 28 formed in the underside of the bristle head 13. The bristle head 13 has an axially threaded opening 29 of a diameter to receive the threaded shank 15 of the handle.

The antiseptic powder receptacle 12 will be filled and sealed at the factory, a closure lid 30 being employed, and when it is desired to use the powder in conjunction with the handle 11 and bristle head 13, the seals 31 are broken and the lid removed. The openings 28 of the bristle head 13 are aligned with the guide pins 27 and moved into seated engagement therewith, thus registering apertures 22 and 26. The reduced extension 14 is now inserted into the opening 19 of the receptacle, until the threaded shank 15 engages in the threaded opening 29 of the bristle head 13. Rotation of the handle 11 will serve to connect the receptacle and bristle head upon the handle. Obviously, when the duster is brought into position for dusting the neck of a customer, the powder will pass through aligned apertures 22 and 26 into the bristles 25 for deposit upon the neck of the customer.

When the powder in the receptacle has been dispensed, the handle and bristle head may be readily disconnected and the empty receptacle is disposed of and replaced by a new filled receptacle; and also at this time, in order to meet health requirements of certain states, a sterilized bristle head may replace the head just removed, for sterilization.

As is readily understood, the duster will be employed at various times when working upon a customer, and in order that the bristles 25 will not come into contact with unclean surfaces, the base of the handle is provided with a plati-

form base 32, which will permit the brush to be supported in an upright position.

While I have shown and described a preferred form of the duster, this is by way of illustration only, and I consider as my own, all such modifications as fairly fall within the scope of the appended claims.

I claim:

1. A barbers' and beauticians' neck duster comprising an antiseptic powder receptacle having an axial opening therethrough and a perforated top, guide pins extended outwardly from the outer face of the top, a bristle head having openings complementary to said guide pins and further having apertures in registry with the 15 apertures of said top, a handle member having

a reduced axial extension complementary to the axial opening of the receptacle, said handle further having a reduced threaded shank for threaded engagement in a threaded opening formed in said bristle head.

2. The structure of claim 1, in which the base of the handle is provided with a planiform surface for upright support of the duster.

CLINTON E. STROUP.
